UNITED STATES PATENT OFFICE.

FREDERIC LANDON TEMPLE, OF CEDAR GROVE, NEW JERSEY, ASSIGNOR TO THE
BRYANT ELECTRIC COMPANY, OF BRIDGEPORT, CONNECTICUT, A CORPORATION
OF CONNECTICUT.

ELECTRIC LIGHTING.

1,044,291.

Specification of Letters Patent. Patented Nov. 12, 1912.

Application filed August 28, 1911. Serial No. 646,461.

To all whom it may concern.

Be it known that I, FREDERIC LANDON TEMPLE, a subject of the King of Great Britain, and residing at Cedar Grove, in the county of Essex and State of New Jersey, have invented certain new and useful Improvements in Electric Lighting, of which the following is a specification.

My invention relates to the art of electric lighting and the object of my invention is to provide means for controlling the lighting of incandescent lamps installed in switch sockets so that the same may be lighted without regard to the position of the socket switch.

In the accompanying drawings, Figure 1 is a side elevation of a socket by which my invention may be carried out in one form; Fig. 2 is a vertical section through a portion thereof on the line 2—2, Fig. 1; Figs. 3 and 4 are exemplary diagrams of different methods of wiring for use in connection with a socket of this character; Fig. 5 is a vertical section through a detail.

In house lighting the most commonly installed lamp socket is one in which a cutout is embodied in the socket structure—the ordinary key, push button, and pull switch sockets being the usual fittings thus employed. In sockets of this character it is impossible to light the lamp unless the socket switch is in the "on" position. Consequently any remote control of lamps in such an installation, without regard to the position of the socket switch, has heretofore been impossible. I now propose to so construct a socket of this type that the same may be controlled from a distant switch without regard to the position of the socket switch. To illustrate my invention I have embodied the same in a key socket of common type which comprises as usual shell and cap A and B, upper and lower insulating buttons 10 and 11 connected by terminal bars 12 and 13 for the wires X and Y the former being connected to the lamp receiving shell 14 by the screw 15 and the latter being connected to the lamp center contact 16 through a cutout mechanism of common type. The mechanism shown comprises a cutout block 17 actuated by the thumb key 18 and subjected to the pressure of the spring 19 which surrounds the standard 20 and bears against the block 17 through the washer 21 sliding on the standard. When

the block is in the "on" position it contacts with the spring arm 22 which is electrically connected to the wire terminal 13 and leads the current therefrom to the center contact through the standard 20. When in the "off" position, the block lies in the position shown in Figs. 1 and 2, spaced from and out of contact with the spring arm 22. As above stated, it has heretofore been impossible to put the lamp in circuit so long as the cutout remains in this position.

In order to permit the lamp to be lighted while its cutout is in the "off" position, I arrange upon the socket a third wire terminal 23 leading to the lamp center contact in the switch circuit through a connection other than the cutout block 17. In the construction shown this connection is effected through the contact arm 24 which projects into the path of and is engaged by the washer 21 as the latter rises under the influence of the spring 19 when the switch block 17 is turned to the "off" position. To this supplemental terminal 23, a wire Z is led through the remote switch 25 (diagrammatically illustrated in Fig. 3), from the main Y which is connected to the wire terminal 13. The socket cutout as above explained is interposed between this terminal 13 and the center lamp contact. As will be readily understood, this supplemental connection to the center lamp terminal makes it possible to light the lamp by merely operating the remote switch 25, while the switch block 17 of the socket switch is in the "off" position.

The utility of the construction is obvious, since with an installation of this character, the entire series of lights in a house may be flashed on in an instant by the operation of the remote switch 25 located for instance in the bed room, and it is impossible for any of the lights to be extinguished except by the breaking of the circuit against this remote switch. On the other hand each lamp is readily controlled by its socket cutout when the remote switch 25 is "off."

Should the number of lights in the series be great enough to make the use of a double pole switch desirable, the system may still be employed by the use of a remote switch of the character illustrated diagrammatically in Fig. 4. Here as will be noted the main X is connected to the terminals 26—27 of the remote switch while the branch Z

from the Y main, is connected to the terminals 28—29. The switch contact 30 which connects the terminals 28, 29 is of the usual two arm character making or 5 breaking the switch on each quarter revolution of the spindle 31. The contact 32 for the terminals 26—27 however has four arms, so that these terminals are connected at 10 every half of the switch spindle 31 and the current passes therethrough even when the circuit through the terminals 28—29 is interrupted, thus permitting the lamp circuit to be made or broken by the socket cutout in the usual fashion.

15 While the invention has been illustrated in a socket of such construction that the supplemental terminal 23 is electrically connected to the center contact only when the 20 socket switch is in the "off" position, obviously it is unnecessary to limit the duration of this supplemental center contact connection to such period, since the connection to the terminal 23 is normally interrupted at the remote control switch and so long as this 25 is "off" a connection between the terminal 23 and the center contact is immaterial. The lamp circuit is then made solely by the operation of the socket switch in precisely the same manner as if the supplemental connection did not exist. In Fig. 5 I have 30 shown a combined standard and wire terminal 33 which may be substituted for the standard 20, terminal 23 and contact arm 24 of Figs. 1 and 2 to establish an unbroken connection between the supplemental wire terminal and the cutout lamp terminal.

35 It must be understood that the socket illustrated is shown merely by way of example and that the supplemental wire terminal and connection to the lamp terminal be- 40

yond the socket cutout may be arranged in various ways not only in the present socket but in other types of sockets without departing from my invention. It will also be realized that the addition of this supplemental terminal does not interfere in any way with the utility of the socket for ordinary installations in which a remote control is not desired. The structure explained gives however an added utility to sockets in 50 which it is embodied and fits them for use in the lighting system explained.

I claim as my invention:—

1. In a lighting system, an electric lamp socket having line wire terminals, lamp terminals, a switch of the make and break type controlling the circuit between the line and lamp terminals, constant connections between the switch terminals and the line wire terminals, in combination with a supplemental wire terminal on the socket for a lead to a remote switch, and a connection between said terminal and a lamp terminal in the socket switch circuit, said connection being closed in the open position of the socket switch, for the purpose described. 55

2. For use in a lighting system, a standard electric lamp socket having a switch of the make and break type in one branch of the lamp circuit, a supplemental wire terminal and a constant connection therefrom to the lamp terminal in the switch circuit, for the purpose described. 70

In testimony whereof I have signed my name to this specification, in the presence of 75 two subscribing witnesses.

FREDERIC LANDON TEMPLE.
